UNITED STATES PATENT OFFICE.

AMOS IVAN ADDISON, OF LONG BEACH, CALIFORNIA, ASSIGNOR TO THE CURTIS CORPORATION, OF WILMINGTON, DELAWARE, A CORPORATION OF DELAWARE.

EXHAUST BOX.

Application filed November 9, 1922. Serial No. 599,775.

To all whom it may concern:

Be it known that I, AMOS IVAN ADDISON, a citizen of the United States, and resident

of Long Beach, in the county of Los Angeles, State of California, have invented new and useful Improvements in an Exhaust Box, of which the following is a specification.

This invention relates to a device for use in canning comestibles. In operations of this character, it is the practice to place the comestible in containers, next heat the containers and their contents, and then immediately to hermetically seal the container.

Heating causes the generation of steam or vapors, and these condense upon cooling of the containers producing a partial vacuum therein. This is known as exhausting, and chambers for heating filled containers in this manner are known as exhaust boxes. It is advantageous to provide a continuous feeding and discharging exhaust box, that is, an exhaust box wherein the cold filled containers enter the exhaust box, travel therethrough and emerge heated and ready for sealing. In order to heat the containers to a sufficiently high temperature, the path of travel of the containers while in the box must be relatively long. The objects of this invention are first, to provide an exhaust box having an endless conveyer to transport containers therethrough; second, to provide an exhaust box which is compact; third, to provide an exhaust box whose heat losses are relatively small; and fourth, to provide certain details of structure whereby a strong, durable, economical, and easily manipulated exhaust box is obtained.

These objects together with other objects and corresponding accomplishments are obtained by means of the embodiment of my invention illustrated in the accompanying drawings, in which:

Fig. 1 is a perspective view looking upon the top of the structure from the front or charging and discharging end, the length of the heating chambers being shown relatively short, in order, to better illustrate the inventive idea; Fig. 2 is a section as seen upon the line 2-2 of Fig. 1; Fig. 3 is an enlarged section as seen on the line 3-3 of Fig. 1; Fig. 4 is a fragmentary perspective view of one unit of the exhaust box, parts being broken out to show the interior structure; Fig. 5 is a perspective view

of a portion of the conveyer; and Fig. 6 is a sleeper for supporting the conveyer track and guards.

Referring more particularly to Fig. 1, the complete device is illustrated. It consists of two chambers 7, each chamber forming a tunnel like unit. Disposed to travel continuously through the chambers in series is an endless conveyer indicated generally in Fig. 1 by the reference numeral 8. A charging chute for feeding containers to the conveyer is indicated by 9, and a discharging chute is indicated by 10.

The heating units are similar and one will be described. Referring more particularly to Fig. 4, a chamber consists of a tube 11 surrounded by a jacket 12. Mounted upon the end of the jacket 12 are flanges 14, to which are bolted rings 15. Each ring 15 is formed with a recess to receive packing 16 held in position by a flange 17, thereby forming a steam tight chamber around the tubular member 11. A plate 18 with an opening therein for the passage of the conveyer and containers is mounted across the front end of each unit. Formed in each jacket 12 is a nipple 19 to receive a steam pipe connected to a pipe 21 which supplies live steam under pressure. Suitable valves are installed to control the flow of steam. A nipple 22 is formed on the jacket 12 and is connected to a pipe 23 communicating with an exhaust pipe 24 for the discharge of the steam. It is obvious that steam supplied through the pipe 21 passes through the jackets 12 to the discharge pipe 24, where it is disposed of in any manner desired. This provides the chambers 11 with heat.

Spaced at suitable intervals along each chamber 11 are sleepers 25, each sleeper having a segmental rib to conform to the curvature of the pipe, supporting faces 27 for rails and an opening 28 for the passage of the conveyer 10. Extending through each heating chamber are rails 29 of angle form for slidably supporting the conveyer plates. Secured to the faces of the sleepers are angle bars 30, to which are secured standards 31. Mounted on the standards are guard rails 32.

Extending through openings in the sleepers in each unit is a humidifying pipe 33. The pipe is provided with a number of perforations through which steam may pass. The humidifying pipes 33 are con-

nected to the steam line 21 by means of fittings indicated generally by 34 and suitable valves control the flow of steam. Live steam may be discharged through the 5 humidifying pipe directly into the heating chambers.

Plates 35 tie the heating chambers together and serve as supports for brackets 36 to which are secured bearings 37 for the 10 shafts of the conveyer wheels 38. The conveyer wheels are sprocket wheels. One of the sprocket wheels is a drive wheel, the driving being accomplished through the shaft by means not shown in the drawing. 15 Passing over the wheels 38 is a chain 39, best shown in Fig. 5. Secured to the links of the chain are plates 40 which slide upon the rails 29. The chain and plates form an endless conveyer, upon which containers 20 may be placed so that they will be carried first through one heating chamber and then through the other. The containers which are usually cans are delivered through the chute 9 to the conveyer which carries 25 through the heating chamber and finally delivers them to the discharge chute 10.

The open cans are passed into the first heating chamber cold. They travel through the chamber absorbing heat which is supplied by the steam in the jacket. The hot steam issuing from the humidifying pipe supplies sufficient moisture so that the contents do not become dry and also supplies heat. The cans pass through the first heating chamber slowly and then through the second heating chamber. In this manner they are within the heating chambers for a relatively long time. It is obvious that if the exhaust box were made in one long chamber, the floor space required would be of 30 awkward dimensions requiring a large space between the workers at the charge and discharge ends. Furthermore, the time that the chain or conveyer would travel on the outside of the heating chamber would be considerable and the amount of heat lost by the chain becoming cooled during its travel outside would become relatively great. With 35 my improved device the chain is traveling substantially all of the time through the heating chambers, and there is substantially no loss of heat from the conveyer. The

length of conveyer is substantially reduced.

What I claim is:

1. An exhaust box comprising the combination of a pair of separate tunnel like heating chambers disposed parallel and adjacent to one another, an endless flexible conveyer rove through said chambers to form a closed loop so as to travel therethrough in 55 series, and driving means geared outside of said chambers to said conveyer and disposed adjacent thereto.

2. An exhaust box comprising the combination of a pair of separate tunnel like 60 jacketed heating chambers disposed parallel and adjacent to one another, said jackets having means to introduce heating fluid thereto, an endless flexible conveyer rove through said chambers to form a closed loop 65 so as to travel therethrough in series, and driving means geared outside of said chambers to said conveyer and disposed at the adjacent ends thereof.

3. An exhaust box comprising the combination of a pair of separate tunnel like 70 jacketed heating chambers disposed parallel and adjacent to one another, the jackets of said chambers having means to introduce heating fluid thereto, an endless flexible 75 conveyer rove through said chambers to form a closed loop so as to travel therethrough in series, driving means geared outside of said chambers to said conveyer and disposed at the adjacent ends thereof, 80 means to feed articles to said conveyer, and means to discharge said articles therefrom.

4. An exhaust box comprising the combination of a pair of separate tunnel like 85 heating chambers disposed parallel and adjacent to one another, an endless flexible conveyer rove through said chambers to form a closed loop 90 so as to travel therethrough in series, having means geared outside of said chambers to said conveyer and disposed at the adjacent ends thereof, 95 means to feed the articles to said conveyer, and means to discharge said articles therefrom.

In witness that I claim the foregoing I 100 have hereunto subscribed my name this 31st day of October, 1922.

AMOS IVAN ADDISON.
